UNITED STATES PATENT OFFICE.

GEORGE MEYER, OF NEW YORK, N. Y.

DESIGN FOR A COUPLING-BAR FOR ENDS OF INTERIOR SECURING-BANDS FOR RUBBER TIRES.

SPECIFICATION forming part of Design No. 32,182, dated January 30, 1900.

Application filed December 27, 1899. Serial No. 741,770. Term of patent 14 years.

To all whom it may concern:

Be it known that I, GEORGE MEYER, a citizen of the United States, residing at New York, in the county of New York and State of New York, have invented and produced a new and original Design for a Coupling-Bar for the Ends of Interior Securing-Bands for Rubber Tires, of which the following is a specification, reference being had to the accompanying drawings, forming a part thereof, and in which—

Figure 1 is a top view of a coupling-bar bearing and incorporating my design. Fig. 2 is a side elevation of same. Fig. 3 is a bottom view of same, and Fig. 4 is a vertical transverse section of same on the dotted line 4 4 of Fig. 2.

The leading feature of my design consists in the form and configuration of the coupling-bar, substantially as shown in the drawings.

In the drawings, A designates the coupling-bar as a whole, which bar is of elongated form

and comprises the base portion B, the outer portion of whose ends incline upwardly, as 25 at a, and the opposite sides of the end portions of which taper inwardly or converge toward one another, as denoted at b b. Longitudinally disposed along the upper surface of the base portion B is the central raised 30 portion C, having a plain upper surface, and at the opposite sides of the transverse center of this portion C are the elongated posts D D, the whole being substantially as shown in the drawings.

What I claim is—

The design for a coupling-bar for the ends of interior securing-bands for rubber tires, substantially as shown and described.

Signed at New York, in the county and 40 State of New York, this 26th day of December, 1899.

GEORGE MEYER.
